US00D832623S

(12) **United States Design Patent** (10) **Patent No.:** **US D832,623 S**
Flaherty et al. (45) **Date of Patent:** **** Nov. 6, 2018**

(54) **DESK**

- (71) Applicant: **Varidesk, LLC**, Coppell, TX (US)
(72) Inventors: **Daniel G. Flaherty**, Irving, TX (US);
David Patton, Flower Mound, TX (US)
(73) Assignee: **Varidesk, LLC**, Coppell, TX (US)
(**) Term: **15 Years**
(21) Appl. No.: **29/603,055**
(22) Filed: **May 5, 2017**

Related U.S. Application Data

- (63) Continuation of application No. 29/512,926, filed on Dec. 23, 2014, now Pat. No. Des. 785,989.

Primary Examiner — John Windmuller*Assistant Examiner* — Steven J Czyz*(74) Attorney, Agent, or Firm* — Venable LLP; Michele V. Frank; Elizabeth C. Gitlin(57) **CLAIM**

The ornamental design for a desk, as shown and described.

DESCRIPTION

FIG. 1 is a front-right perspective of a desk according to the claimed design shown in a lowered position; FIG. 2 is a front view of the desk of FIG. 1; FIG. 3 is a rear view of the desk of FIG. 1; FIG. 4 is a left side view of the desk of FIG. 1; FIG. 5 is a right side view of the desk of FIG. 1; FIG. 6 is a top view of the desk of FIG. 1; and, FIG. 7 is a front-right perspective of the desk of FIG. 1 shown in a raised position. The features shown in broken lines represent portions of the desk which form no part of the claimed design.

1 Claim, 7 Drawing Sheets# US D832,623 S
